CLAIM

The ornamental design for a control resistor for an automobile blower motor, as shown.

DESCRIPTION

FIG. 1 is a front elevational view of a control resistor for an automobile blower motor showing our new design;

FIG. 2 is a right side elevational view thereof;

FIG. 3 is a top plan view thereof;

FIG. 4 is a left side elevational view thereof;

FIG. 5 is a rear elevational view thereof;

FIG. 6 is a bottom plan view thereof;

FIG. 7 is a front and upper left perspective view thereof; and,

FIG. 8 is a front and lower left perspective view thereof.

FIG. 1

FIG. 2

FIG. 3

FIG. 4

FIG. 5

FIG. 6

FIG. 7

FIG. 8
